COMBINED COCK AND SWITCH DEVICE

Filed March 14, 1930

UNITED STATES PATENT OFFICE

HARRY F. WOERNLEY, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA

COMBINED COCK AND SWITCH DEVICE

Application filed March 14, 1930. Serial No. 435,765.

This invention relates to combined cock and switch devices, and more particularly to that type used on railway cars for controlling electric train line circuits and for controlling the operation of car coupler uncoupling mechanisms.

The principal object of my invention is to provide an improved combined cock and switch device having means for insuring the proper assembly of the several parts thereof.

Another object of my invention is to provide a combined cock and switch device in which the plug valve of the cock portion may be removed and replaced without disturbing the switch portion.

Other objects and advantages will appear in the following more detailed description of the invention.

In the accompanying drawing; Figure 1 is a sectional view of a combined cock and switch device embodying my invention, taken on the line 1—1 of Fig. 2; Fig. 2 is a cross sectional view of the same taken on the line 2—2 of Fig. 1; and Figs. 3 and 4 are fragmentary cross sectional views taken on the lines 3—3 and 4—4, respectively, of Fig. 1.

As shown in the drawing, the combined cock and switch device is of the same general type as the cock and switch device shown and described in Patent No. 1,269,253, of Thomas R. Brown, issued June 11, 1918, and is especially adapted for use in equipments of the type shown and described in my Patent No. 1,571,222, issued February 2, 1926, although with slight modifications in the valve portion it may be used in the equipment described in the above referred to Brown patent.

When my improved device is used in the type of equipment shown and described in my aforementioned patent, the valve portion thereof will take the place of the "valve 43" of the patent.

The cock portion of my improved device may, if desired, be made in the form of an angle cock such as is shown and described in Patent No. 1,649,023, of Clyde C. Farmer, issued November 15, 1927.

My combined cock and switch device comprises a switch portion 1 and a cock portion

2, the cock portion being preferably arranged above the switch portion.

The switch portion may comprise a bracket 3 having a base portion 4 provided with lugs 5 for attachment to a car body. Integral with the base portion 4 and extending upwardly therefrom are three unevenly spaced supports 6 upon the upper ends of which a cover plate 7 rests. The casing of the switch portion comprises a flexible band 8 of sheet metal which is drawn and removably held in close engagement with the base portion 4 of the supporting bracket 3 and cover plate 7 by means of a suitable clamping mechanism 9.

Contained within the casing of the switch portion 1, and secured to one of the supports 6, is an insulating member 10, and fixed to this member, are spaced contacts 11 and 12 which are connected to train line circuit wires 13 and 14 respectively. Two of such sets of contacts are shown, but it will be understood that one or any number may be employed, depending upon the number of circuits it is desired to control by the switch portion.

Also contained within the casing of the switch portion 1 are connected contacts 15 and 16 which are movable into and out of contact with the contacts 11 and 12 respectively for closing and opening the train line circuit or circuits as the case may be. These contacts 15 and 16 are moved through the medium of an operating shaft 17 which, at its lower end is rotatably mounted in the base portion 4 of the bracket 3. The upper end portion of this shaft is secured, by a pin 18, to the lower end portion of a coupling member 19, and this portion of the coupling member is journaled in the cover plate 7, thus forming a bearing for the upper end of the shaft.

The cock portion 2, as before mentioned, is arranged above the switch portion 1 and the casing thereof rests on the cover plate 7 and is secured to the supports 6 of the bracket 3 by stud bolts 20 which pass through the casing and plate 7 and have screw-threaded connections with the supports 6, the plate 7 being rigidly clamped between the casing of the cock portion and the upper ends of the supports 6. It will here be noted that since the

100

supports 6 are unevenly spaced, the proper positioning of the cock casing is insured.

Mounted in a bushing 21 which is rigidly secured in the casing of the cock portion 2, is 5 a rotatable plug valve 22 having a passage 23 adapted in one position to register with ports 24 and 25 in the bushing 21 and establish communication from a chamber 26 to a chamber 27, which chambers, if the device is used in 10 connection with the type of equipment shown and described in my aforementioned patent, are respectively connected by pipes 28 and 29 to a fluid pressure supply source such as a main reservoir and the mechanisms for re- 15 tracting the usual contact carrier, the closing off of the flow of fluid through the train pipe to the face of the coupler and the unlocking of the couplers.

The plug valve 22 is cut away at 30 and 20 together with the bushing 21 defines a passage through which the chamber 27 is connected to a passage 31 leading to the atmosphere when the valve is in the position shown in Figure 4.

25 The plug valve 22 tapers from its greatest diameter at its top to its least diameter at its bottom. Interposed between and engaging the top surface of the valve and the inner surface of a cap nut 32 which has screw- 30 threaded connection with the casing is a spring 33, the pressure of which tends to maintain the valve in its proper position in the bushing 21.

35 The axes of the shaft 17, coupling member 19 and plug valve 22 are preferably in vertical alignment. Preferably integral with the plug valve and depending from the lower end thereof and slightly offset from the center of the valve, is a rectangular lug 34 which is received in a corresponding groove 35 formed 40 in the upper end of the coupling member 19.

45 The upper end portion of the coupling member 19 is received in a recess 36 formed in the casing of the cock portion, which recess is enlarged at 37 to receive a horizontally disposed projection 38 which may be in the form of a pin carried by the upper end portion of the coupling member.

50 For the purpose of rotating the coupling member 19 and thereby the plug valve 22 and shaft 17, a removable handle 39 is provided, which handle, for a portion of its length, extends between the casing of the cock portion and the cover plate 7. The inner end portion 55 of the handle is provided with spaced jaws 40 adapted to operatively engage opposite sides of a rectangular portion 41 of the coupling member 19, said rectangular portion 41 being located intermediate the ends of the member.

60 The handle adjacent its inner end is provided with an upwardly extending projection 42 which is adapted to be received in a groove formed in the casing of the cock portion, which groove has a portion 43 radially arranged relative to the axis of the coupling

member and a portion 44 which is concentric with the periphery of the coupling member, the outer end of the portion 43 being open. This groove permits of the easy removal and replacement of the handle when the handle is 70 in neutral position as shown in the drawing and prevents the removal thereof when it is in uncoupling position.

As shown in the drawing, when the handle is in neutral position, the passage 23 of the 75 plug valve 22 will be out of registration with the ports 24 and 25 of the bushing 21 and the flow of fluid from the chamber 26 to the chamber 27 is closed off and the chamber 27 is vented to the atmosphere by way of the 80 port 25, space 30 between the plug valve and the bushing, and the passage 31. Further, with the handle in neutral position, the 85 switch contacts 15 and 16 will be in contact with the stationary contacts 11 and 12 respectively, thus closing the train line circuits.

When the handle 39 is operated from neutral position toward uncoupling position, the contacts 15 and 16 are moved out of contact 90 with the stationary contacts 11 and 12 respectively, thus opening the train line circuit or circuits to the face of the usual contact carrier, after which the continued rotation of the plug valve 22 by the use of the handle 39 95 brings the passage 23 of the plug valve into registration with the ports 24 and 25 in the bushing 21 so that the chamber 26 is in communication with the chamber 27 and fluid under pressure supplied to the chamber 26 100 through the pipe 28 may flow to the uncoupling mechanism by way of pipe 29.

In assembling the switch portion 1, the 105 movable contacts 15 and 16 are mounted in their proper positions relative to the shaft and then the lower end of the shaft is seated in the base portion 4 of the bracket. The lower end of the coupling member 19 is now passed through the bearing opening in the plate 7 to such a position that the projection 38 engages the upper surface of the plate 7. The 110 plate and coupling are now lowered so that the slot in the lower end of the coupling member receives the upper end of the shaft 17.

Now when the coupling member is in its proper position on the shaft and the plate 115 held against the projection 38 there will be sufficient room to insert the securing pin 18. After the pin 18 is inserted, the plate 7 is permitted to move downwardly covering the 120 ends of the openings in which the pin has been inserted. The cover plate 7 and casing of the cock portion 2 are secured in place by the bolts 20. Should the coupling 19 be mounted in the wrong position relative to the 125 movable contacts 15 and 16, the casing of the cock portion will engage the projection 38 carried by the coupling member 19, and by reason of such engagement, the casing will not seat properly, so that the workman assembling the device will know that the cou-

130

pling member is not mounted in its proper position and that the position of the coupling must be changed so that the projection 38 will be within the enlarged portion 37 of the 5 recess 36, thus insuring the proper positioning of the coupling.

After the casing and cover plate are secured in place, the bushing 21 and plug valve 22 may now be inserted through an opening in 10 the top of the casing. Now since the coupling can only be in its proper position relative to the contacts 15 and 16, and the lug 34 of the plug valve must extend into the groove 35, the proper positioning of the plug valve 15 relative to the contacts 15 and 16 is insured. With the plug valve positioned, the spring 33 is placed on the upper end thereof and finally the cap nut 32 is screwed into the casing, compressing the spring 33.

20 If desired, the several parts of the cock portion 2 may be mounted in the casing separately from the switch portion and then be mounted on the switch portion as a unit.

From the foregoing description it will be 25 seen that I have provided a combined cock and switch device in which the proper positioning of the several parts thereof is insured and in which the plug valve of the cock portion thereof may be readily removed and re- 30 placed without removing the switch casing or the cock casing and without removing any portion of the switch mechanism.

While one illustrative embodiment of the invention has been described in detail, it is 35 not my intention to limit its scope to that embodiment or otherwise than by the terms of the appended claims.

Having now described my invention, what I claim as new and desire to secure by Letters Patent, is:—

1. A combined cock and switch device comprising a cock portion and a switch portion, a rotatable valve included in said cock portion, a switch included in said switch portion, a shaft for operating said switch, a member through the medium of which said shaft and valve are simultaneously rotated, said valve and switch having predetermined fixed positions with respect to each other, and 45 a projection on said member adapted to be engaged by the cock portion to prevent the cock portion from being operatively connected with the switch portion when said switch is not in its proper position in initially assembling the device.

2. A combined cock and switch device comprising a cock portion and a switch portion, a rotatable valve included in said cock portion, a switch included in said switch portion, a shaft for operating said switch, a member through the medium of which said shaft and valve are simultaneously rotated, said valve and switch having predetermined fixed positions with respect to each other, a projection 55 on said member adapted to be engaged by

said cock portion to prevent the cock portion from being operatively connected with the switch portion when said switch is not in its proper position in initially assembling the device, and a lug on said valve adapted to operatively engage said member only when said member and valve are in their proper positions relative to each other.

3. A combined cock and switch device comprising a cock portion and a switch portion, 75 a casing for said switch portion, a rotatable switch operating shaft contained in the switch casing, a casing for said cock portion, a plug valve in said casing, said valve tapering from its greatest diameter at its top to its least diameter at its bottom, and a member connecting said valve and shaft and through the medium of which said valve and shaft are adapted to be rotated, said valve being adapted to be removed and replaced without 80 disturbing either of said casings or said member.

4. A combined cock and switch device comprising a cock portion and a switch portion, 90 a casing for said switch portion, a rotatable switch operating shaft contained in the switch casing, a casing for said cock portion, a plug valve in said casing, said valve tapering from its greatest diameter at its top to its least diameter at its bottom, and a member 95 connecting said valve and shaft and through the medium of which said valve and shaft are adapted to be rotated, said valve being adapted to be removed and replaced through an opening in the top of the cock casing 100 without disturbing either of said casings or said member.

5. A combined cock and switch device comprising a cock portion and a switch portion, 105 a casing for said switch portion, a rotatable switch operating shaft contained in the switch casing, a casing for said cock portion, a plug valve in said casing, said valve tapering from its greatest diameter at its top to its least diameter at its bottom, and a member 110 connecting said valve and shaft and through the medium of which said valve and shaft are adapted to be rotated, said valve being adapted to be removed and replaced from the top of the cock casing without disturbing the other parts of said devices.

6. A combined cock and switch device comprising a cock portion and a switch portion, 115 a casing for said switch portion, a plurality of unevenly spaced supports included in said casing, and each support having a tapped recess for the reception of a securing bolt, a casing for said cock portion supported by said supports and having openings adapted to register with said tapped recesses when the cock casing is in its proper position relative to the switch casing, and bolts securing the cock casing to said supports.

7. A combined cock and switch device comprising a cock portion and a switch portion, 120

a casing for said switch portion, rotatable switch means journalled in said casing, a casing for said cock portion having a bore therethrough open at each end, a rotatable 5 valve mounted in the casing of the cock portion within said bore and operatively connected with said switch means, means removably secured to the casing of the valve portion for closing the outer end of the bore and 10 for maintaining the rotatable cock in opera-

tive engagement with the switch means, said valve being adapted to be removed and replaced through the outer end of said bore without disturbing either of said casings or said switch means when the means for maintaining the valve in engagement with the switch means is removed from the casing of the valve portion, and means for rotating said switch means.
